UNITED STATES PATENT OFFICE.

LOUIS SMITH, OF CHICAGO, ILLINOIS, ASSIGNOR OF ONE-HALF TO WILLIAM L. HALL, OF CHICAGO, ILLINOIS.

PROOF AND TRANSFER PRESS.

1,312,366.

Specification of Letters Patent.

Patented Aug. 5. 1919.

Application filed September 14, 1918. Serial No. 254,151.

To all whom it may concern:

Be it known that I, LOUIS SMITH, a citizen of the United States, and a resident of Chicago, in the county of Cook and State of Illinois, have invented certain new and useful Improvements in Proof and Transfer Presses; and I do hereby declare that the following is a full, clear, and exact description thereof, reference being had to the accompanying drawings, and to the characters of reference marked thereon, which form a part of this specification.

This invention relates to novel proof and transfer presses for taking proofs from forms suitably locked on a bed for proving and registering the form and thereafter, without removing the forms from the bed after the same is in register, transferring the impressions from the forms direct on printing plates for lithographic or offset presses. The press is designed for making either positive or negative transfer printing plates or elements for lithograph or offset presses from zinc, aluminum, stone, rules, type, or cuts in one operation, in one or more colors. One or more forms can be made on a printing plate by direct transfer from rules, type, or cuts, to zinc plate, aluminum, or stone.

The purpose of the invention is to provide a novel construction, wherein a proof and a transfer roller may be so associated with a bed on which the forms are locked and a bed on which the transfer plates, stones, or other elements, are supported that the forms may be first proved up and registered by running the proof roller thereover, and thereafter the impressions from the forms directly transferred therefrom by a transfer roller or rollers to a printing element such as zinc printing plates, aluminum or stone for lithograph work or offset work, thus providing in one simple press means for successively proving and transferring the work, which may be employed for lithograph work only or for offset work only, and which may be used also as a proving press for composing room.

Another object of the invention is to provide a novel press of this character wherein the bed that supports the printing forms may be adjusted with respect to the proof roller and to the transfer roller or rollers, so as to adjust the press to forms of different sizes locked on the bed. Such adjustment of the bed may be effected either in a direction

parallel to the axes of the proof or transfer rollers or in a direction transverse thereon, as the adjustment may be in both directions.

Another object of the invention is to provide novel means for so adjusting the bed.

A further object of the invention is to provide means for operating the rollers, constructed and coöperating with means for elevating the rollers above the forms and printing elements so that said rollers may be moved longitudinally of the bed without contact with certain of the forms or plates at times when no contact is desired, and in contact therewith when such contact is desired.

Another object of the invention is to provide a novel arrangement of sectional tracks for supporting the rollers, in connection with means for giving movement to the rollers bodily of the bed and printing elements, so constructed and arranged as to elevate the sectional tracks to lift the rollers above the forms and printing elements at certain parts of the travel of the rollers.

Another object of the invention is to provide a novel arrangement of transfer rollers whereby the impression from the printing forms may be either transmitted directly to a printing plate, stone, or the like, as a negative impression or directly transmitted to a second roller for direct positive transfer to a printing plate for an offset press.

A further object of the invention is to provide a support in a device of this character for such printing plates so arranged as to permit the plates to be shifted so that the required number of transfers may be made on the transfer roller and transferred to the printing plates.

Other objects of the invention are to improve and simplify proof and transfer presses, and the invention consists in the combination and arrangement of the parts shown in the drawings and described in the specification, and is pointed out in the appended claims.

In the drawings,

Figure 1 is a plan view of a proof and transfer press embodying my invention.

Fig. 2 is an enlarged plan view of the front end of the press with parts broken away.

Fig. 3 is an enlarged rear end of the press with parts broken away.

Fig. 4 is a detail of one of the transfer

rolls on the line 4—4, showing means for locking the roll to rotate with its traveling gear and to permit the gear to rotate without causing the roll to rotate.

6 Fig. 5 is an enlarged side elevation of the front end of the machine.

Fig. 6 is a longitudinal section thereof on the line 6—6 of Fig. 9.

10 Fig. 7 is an enlarged side view of the rear end of the machine.

Fig. 8 is a longitudinal section thereof, taken on the line 8—8 of Fig. 1.

Fig. 9 is a cross section on the line 9—9 of Fig. 2.

15 Fig. 10 is a cross section on the line 10—10 of Fig. 3.

The frame 15 of the machine may be made of any suitable or convenient shape to properly support the elements of the machine 20 and their bearings, and is shown as comprising a horizontal platform supported on legs or standards. It has an extension 16 for a purpose to be hereinafter described. Supported on said frame is a movable or adjustable printing form supporting bed 17 and a fixed bed 65 to support printing elements 66. The movable or adjustable bed, as herein shown, is made of a width substantially equal to the width of the frame and of a 30 length to extend throughout the principal distance between the proof roller and the fixed bed 65. The printing plate supporting bed 65 is raised above the level of the bed 17 so that the latter in its longitudinal 35 adjustment may pass partly beneath the bed 65, as indicated in dotted lines in Fig. 1, and for a purpose hereinafter described. The frame 15 is also provided at one end with a transverse extension 76 to support an adjustable bed 78 for printing plates 77, hereinafter described. The bed 17 may be termed a double bed in that it is arranged to support two or more forms which are adapted to be registered to produce the ultimate 40 composition.

45 For convenience and certainty, the forms supported on the bed 17 are herein termed printing forms; the plates 66 supported on the fixed bed 65 are termed negative printing elements, and the plates 77 supported on the adjustable bed 78 are termed positive printing elements. These terms are not, however, intended as limiting terms but are descriptive of the present illustration of the invention.

50 Said bed 17 supports frame or chases 18 in which are locked in any suitable manner the forms 18' best shown in Fig. 1. The particular forms shown in Fig. 1 may be the down and cross line forms that are composed in proper register for printing cross ruled sheets in accordance with the method disclosed in my prior United States Letters Patent Number 1,210,862, granted January 2, 1917. The cross ruled forms made in ac-

cordance with the aforesaid method, may bear in addition to the down and cross lines, such printing as may be desired. As shown in Fig. 1, the forms 18' are of dimensions to occupy allotted rectangular spaces 18² on 70 the bed, and, as herein shown, the transverse width of each space is equal to one-half the length of the proof and transfer rollers.

Assuming that proofs are to be made of down and cross lines of a cross ruled form, 75 after proofs have been taken from the full line forms shown in Fig. 1 on one-half of the proof roller, the bed supporting said forms may be shifted so that the forms occupy the positions indicated in dotted lines in Fig. 1, 80 and the same proofs taken on the other half of the proof roller.

If desired, however, other forms, such as plates, rules, type, or cuts of the same or different colors be locked on the bed to constitute smaller forms, in which event it is desirable to adjust the movable bed both laterally and longitudinally of the frame so as to bring the forms in proper registration with desired longitudinal and circumferential 90 areas of the proof and transfer rollers.

95 The means herein shown for laterally adjusting the movable bed comprises a threaded shaft 20 which is rotatably mounted in a suitable bearing 20' on the frame and is threaded through a nut 21 that depends from the bed (Fig. 9). Said shaft is provided with a hand wheel 22 and a graduated dial; co-operating pointer 22^a (Figs. 2 and 5) may be associated with said shaft so as to 100 facilitate the registration of the forms relatively to the proof and transfer roller. The extension 16 of the frame 15 is provided to support the bed 17 when the latter is adjusted to occupy the position indicated by 105 the dotted lines in Fig. 1.

25 designates the proof roller which is located at the forward end of the frame. It is supported on a shaft 25' that is rotatively mounted in bearings carried by bearers 40 110 which are in turn supported on tracks 41, 41', the latter fixed relatively to the frame and the former vertically adjustable, as hereinafter described. 26, 26 designate spur gears which are fixed to said shaft 25' or to 115 the roller 25 and mesh with the upwardly facing teeth of racks 27, 27 that are supported on the frame 15 at the sides thereof whereby, on rotation of the proof roller, the latter is caused to rotate on its axis and also 120 to be carried bodily lengthwise of the adjustable bed. The said proof roller is rotated on its axis and caused to move along the plate by means of a crank 28 fixed to the shaft 25'. The track sections 41 are adapted to be raised in any suitable or preferred manner to lift the proof roller out of contact with the forms or certain of them, as will hereinafter more fully appear. 29 designates a group of inking rollers of any 125

suitable type associated with an ink fountain and adapted to travel over the forms when the proof roller is caused to bodily pass over the bed to ink said forms.

- 5 The means for adjusting the bed 17 longitudinally of the frame to register the forms to predetermined peripheral areas of the proof roller comprise a rotative shaft 32 that is disposed transversely of the frame 10 and is mounted in suitable bearings 32' thereon. Said shaft 32 carries near its end pinions 33 which are adapted to mesh with the downwardly facing teeth of racks 34 suitably fixed to the bed 17. The shaft 32 15 is provided at one end with a hand wheel 35 by which it is rotated, and a graduated dial 35^a and a co-operating pointer may be associated with the shaft to measure the rotations of the shaft and thereby facilitate registration of the forms relatively to the proof 20 and transfer rollers.

Through the coaction of the adjusting shaft 20 and nut 21, on the one hand, and the shaft 32 and the pinions 33 and racks 34, 25 on the other hand, it will be observed that the bed 17 may be shifted either laterally or longitudinally of the frame to effect desired registration of the forms relatively to the proof and transfer rollers and to adjust the 30 press to forms of different sizes. The threads of the shaft 20 and the teeth of the pinion 33 and racks 34 will be made of such pitch as to give a desired delicacy of adjustment of the bed in either direction, and the 35 dials 22^a and 35^a are graduated to indicate such adjustments. It will be understood that the pointers of said dials are geared in any suitable manner to the shafts 20 and 32 to cause the pointers to sweep over the dials 40 as said shafts are turned to adjust the bed.

The shoes or bearers 40, in which the shaft 25' of the proof roller is mounted bear upon the fixed tracks 41' of the frame at the front end of the press when the proof roller 45 is in its inoperative or retracted position and when said roller is moved over the forms 18' said bearers 40 are supported by the sectional tracks 41. When the forms are of such size as to occupy less area than all of 50 the bed, or when proving multi-color forms on the bed, it will be necessary in some parts of the travel of the proof roller over the form to lift the same away from or out of contact with certain of the forms. Such 55 lifting of the proof roller may be effected by raising the sectional tracks 41 and said tracks may be raised in any suitable or approved manner. The means herein shown for raising the tracks are made as follows:

60 The said track sections are provided at their ends and on their under sides with shallow cam faces adapted to be engaged by the inner arms 45 of levers 43 that are pivoted at 44 to the machine frame. When the 65 levers 43 are in their outstanding positions,

or normal to the sides of the frame, as shown in Fig. 3, the arms 45 are engaged with said cams and serve to raise the tracks to positions indicated in Figs. 5 and 6. When the proof roller is located abreast said 70 tracks and the bearers 40 are supported on the raised tracks, said bearers and the proof roller are raised so as to lift the roller above the forms. When the levers 43 are swung at oblique angles to the positions indicated in 75 Figs. 1, 2, 5, and 7, the tracks 41 descend to the level of the fixed tracks 41' of the frame to bring the proof roller in contact with the forms on the bed as desired.

50 designates a transfer roller, the shaft 80 51 of which is mounted in suitable bearings carried by bearers 56 that are adapted to bear on the fixed tracks 41' of the frame or upon the sectional raisable and lowerable track sections 41. The shaft 51 of said 85 transfer roller is adapted to be rotated on its axis through the medium of a hand crank 52 attached to the said shaft. At the ends of the transfer roller are spur gears 53 which mesh with the upwardly facing teeth 90 of the rack 27, above referred to, whereby when the crank 52 is turned, and there-through the transfer roller 50, the engagement of said gears 53 with the tracks 27 causes the transfer roller 50, not only to 95 rotate on its axis, but also to be moved bodily lengthwise of the beds 17 and 65. Thus the transfer roller may be moved over the forms 18' after the same have been proven and said transfer roller may be 100 thereafter moved backwardly over the bed 17 and to the bed 65 to transfer the impressions received thereby on the printing elements 66 supported on the fixed bed. When said transfer roller 50 is being moved 105 forwardly over the fixed bed 65, the track sections 41 are elevated to lift said roller out of contact with the printing element 66 and when the roller is returned to said printing element after receiving the transfer from the forms 18', the track sections 110 are depressed to cause the impression received by the transfer roller to be transferred to said printing element. Also the track sections 41 may be thus raised to lift 115 the transfer roller out of contact with any one of the forms 18' not to be transferred in any particular operation of the machine.

If the plates 66 on the bed 65 are to be 120 used as lithograph plates on a lithograph press, the transfer of the forms on said plate or element will be negative or the same as shown on the forms 18', and said plates after receiving the transfer from the roll 50 125 are removed to be prepared for the lithograph press and used as printing plates in the usual way.

At times it is desirable to move the transfer roller 50 bodily lengthwise of the bed 130

without turning it on its axis. This may be effected in any suitable or known way. One form of means for causing the transfer roller 50 to be thus moved longitudinally of the bed without rotating it on its axis is shown in Fig. 4. As therein shown, the shaft 51 of the transfer roller is grooved to receive keys 60, 60 having hand pieces 61 exposed at the ends of the shaft, whereby the keys 10 may be shifted in the keyway. The heads of the transfer roller 50 are provided with keyways 63 and the spur gears 53 are also provided with keyways 62. When the broad inner ends of the keys 60 are engaged partially in the keyways 62 of the spur gear and partially in the keyways 63 of the transfer roller, said transfer roller is locked to the gears 53 so that when the shaft 51 is rotated, through application of power to 20 the crank shaft 42, the transfer roller will be caused to rotate on its axis and also to be moved bodily longitudinally over the bed through the coaction of the spur gears 53 and the racks 27. When the keys 60, 60 are 25 shifted so that its broader inner ends lie wholly within the keyways 63 of the spur gears 53, said gears may rotate with the shaft 51, without, however, transmitting rotation to the transfer roller 50. In the latter 30 adjustment of the parts the transfer roller may be shifted bodily, through the coaction of the gears 53 and rack 27 with respect to the bed without turning on its axis. The keys may be connected in any suitable manner 35 for mutual operation, as for instance in the manner shown in Fig. 4.

When it be desired to transfer the impressions from the transfer roller 50 for positive impression to printing elements for 40 offset press work, the impression from the transfer roller 50 is transferred directly to a second transfer roller 70 that is so mounted on the frame that said transfer rollers 50 and 70 may be geared together to rotate in 45 peripheral contact with each other and at equal speed and thereby transfer the impression from one roller to the other.

The said transfer roller 70 is mounted on a shaft 71 which is rotatively supported on 50 and is carried by bearers 71' that are supported directly on the fixed tracks 41' of the frame. In order to cause the transfer rollers 50 and 70 to be rotated in contact with each other and at equal peripheral 55 speeds, said rollers are provided at their ends with meshing gears 72, as best shown in Fig. 3. The shaft 71 of the transfer roller 70 is provided with a crank 73 by which the latter roller is turned on its axis 60 and, through coaction of spur gears 74, 74 at the ends thereof with the racks 27 before described, said transfer roller 70 may be caused to be moved bodily over and in contact with the printing element 77 to transfer 65 the impression received from the roller

50 to the positive printing elements for offset work.

When the transfer rollers 50, 70 are to be rotated in peripheral contact with each other to transfer an impression from one 70 to the other, broad, inner ends of the keys 60, 60' of the transfer roller 50 may be forced inwardly wholly into the keyways 63 of the transfer roller 50, whereby said roller is released from the spur gear 53 so that the 75 roller may be rotated on its axis without, however, causing said roller to move bodily relatively to the frame. The transfer roller 70 may be likewise provided with controlling keys 75 by which said latter roller may 80 be also released from its spur gears 74 so that both said rollers 50 and 70 may be caused to rotate on their axes and in peripheral contact with each other without tendency of moving the rollers bodily relatively 85 to each other, this occurring when an impression is to be transferred from the primary transfer roller 50 to the secondary transfer roller 70, and the impression thereafter transferred from the latter roller to the 90 printing element 77.

The bed 78 is adjustable transversely of the frame 15 so that impressions may be transferred to a number of printing elements 77 whose aggregate length is greater than the 95 length of the transfer roller 70. Such adjustment of the bed 78 may be effected by providing the bed with downwardly facing racks 80 (Figs. 3 and 7) which are adapted to be engaged by pinions 81 that are fixed to a rotative shaft 82 disposed transversely of the frame 76 and mounted in suitable bearings therein, and provided at one end with a hand crank.

In the operation of the machine, the proof 105 roller will turn on its axis during the time it is being moved bodily rearwardly over the forms to receive proof impressions therefrom, and will be released from its gears so as to be carried bodily forwardly over the 110 forms without turning on its axis, said proof roller returning to its normal or inoperative position while the interrupted or cut away portion thereof faces downwardly. It will also be understood that the transfer roller 115 50 will be rotated on its axis when traveling forwardly over the printing forms 18' to receive the impressions therefrom, and that when traveling backwardly over the movable and fixed beds 17 and 65, respectively, it 120 will be released from its gears so as not to turn on its axis, and during its return movement the cut away or interrupted portion thereof will face downwardly. So likewise, the secondary transfer roller 70 will turn on 125 its axis when moving rearwardly over the printing element 77 but will be disengaged from its gears and return forwardly to its inoperative position without rotating on its axis.

The means herein shown for releasing the gears from the proof and transfer rollers are merely illustrative as one form of such means, but it will be understood that any 5 preferred or known form for controlling the movement of the rollers to cause them to rotate when traveling in certain directions and to hold them from rotation when traveling in other directions may be employed.

10 In event that the key means herein shown be employed, the frame may be provided with any suitable cams to coöperate with the keys, or in place of the keys known forms of ratchet release and co-acting projections on 15 the frame may be employed.

So far as the structural details of the various mechanisms by which to operate the proof and transfer rollers and by which to elevate and depress the rollers at the desired 20 times and by which to adjust the movable beds 17 and 78 are concerned, such details may be considerably varied from those shown, said details being merely illustrative rather than limiting. It is believed, however, that the combination of the proof and 25 transfer rollers operating on a single frame in connection with a movable or adjustable printing form bed and with a bed or beds 30 for supporting the printing elements to receive the impressions from the transfer rollers is novel and such combination and the general adaptation of the means to effectuate said combination are herein broadly claimed.

I claim as my invention,—

- 35 1. A proof and transfer press comprising an adjustable bed adapted to support a printing form, a fixed bed adapted to support a printing element, a proof roller travelable over the printing form, and a transfer roller travelable across the printing element and over the printing form to receive an impression from said form and to transfer said impression to the printing element.
- 45 2. A proof and transfer press comprising an adjustable bed adapted to support a printing form, a fixed bed adapted to support a printing element, a single frame to support said beds, a proof roller travelable over the printing form, and a transfer roller travelable across the printing element and over the printing form to receive an impression from said form and to transfer said impression to the printing element.
- 55 3. A proof and transfer press comprising an adjustable bed adapted to support a printing form, a fixed bed adapted to support a printing element, a single frame to support said beds, a proof roller travelable over the printing form, a transfer roller travelable across the printing element and over the printing form to receive an impression from said form and to transfer said impression to the printing element, and means to adjust 60 said movable bed relatively to said rollers.

4. A proof and transfer press comprising an elongated bed adapted to support a printing form, a fixed bed adapted to support a printing element, a proof roller travelable over the printing form, a transfer roller travelable across the transfer element and over the printing forms to receive an impression from said form and to transfer said impression to the transfer element, and means to lift the transfer roller out of contact with the printing element and printing 75 form.

5. A proof and transfer press comprising a bed adapted to support a printing form, a fixed bed adapted to support a printing element, a proof roller travelable over the printing form, a transfer roller travelable across the printing element and over the printing form to receive impressions from said form and to transfer said impression 80 to the printing element, and means to support said form bed constructed with means to adjust the latter bed laterally and longitudinally relatively to said rollers.

6. A proof and transfer press comprising a proof roller, a transfer roller and an adjustable and a fixed bed common to said rollers.

7. A proof and transfer press comprising a movable form bed, a fixed printing element bed, rotatable proof and transfer rollers, and means to cause the said rollers to rotate on their axes and to travel over said beds.

8. A proof and transfer press comprising a movable form bed, a fixed printing element bed, a proof roller, with means to rotate it and to cause it to travel over the form bed, and a transfer roll with means to rotate it and to cause it to travel over said beds toward and from the proof roller.

9. A proof and transfer press comprising a movable form bed, a fixed printing element bed, a proof roller, with means to rotate it and to cause it to travel over the form bed, a transfer roller with means to rotate it and to cause it to travel over the said beds toward and from the proof roller, tracks on which said rolls are supported, and means to raise and lower said tracks.

10. A proof and transfer press comprising a frame, a printing form bed supported thereon, means to adjust said bed transversely and longitudinally of the frame, a proof roller travelable over said bed, and raisable and lowerable tracks on which said proof roller is supported.

11. A proof and transfer press comprising a frame, a printing form bed supported thereon, means to adjust said bed transversely and longitudinally of the frame, and proof and transfer rollers coöperating with said bed.

12. A proof and transfer press comprising a frame provided with a lateral bed sup-

- porting extension, a bed supported on the frame, with means to adjust it laterally and longitudinally of the frame, a proof roller supported on said frame, and means to cause said roller to travel over said bed.
13. A proof and transfer press comprising a frame, a bed supported thereon, tracks at the sides of the frame, proof and transfer rollers, bearers on which said rollers are rotatively supported and adapted to travel on said tracks, means to rotate said rollers, and means to cause them to separately travel over said bed.
14. A proof and transfer press comprising a frame, a bed supported thereon, tracks at the sides of the frame, proof and transfer rollers, bearers on which said rollers are rotatively supported and adapted to travel on said tracks, means to rotate said rollers, and means to cause them to separately travel over the bed, said tracks being sectional, and means to raise and lower the track sections.
15. A proof and transfer press comprising a frame, a bed supported thereon, tracks at the side of said frame, proof and transfer rollers, bearings therefor travelable on said tracks, racks on the frame parallel to said tracks, gears on the rollers meshing with said racks, and means to separately rotate said rollers.
16. A proof and transfer press comprising a frame, a bed thereon, proof and transfer rollers rotatively supported on said frame, racks on said frame, gears on said rollers to mesh with said racks, and means to raise and lower said rollers relatively to said bed.
17. A proof and transfer press comprising a frame, a bed supported thereon, tracks at the side of said frame, proof and transfer rollers, bearings therefor travelable on said tracks, racks on the frame parallel to said tracks, gears on said rollers meshing with said racks, means to separately rotate said rollers, and means to releasably lock the roller gears to said rollers, whereby said gears may rotate independently of or together with said rollers as desired.
18. A proof and transfer press comprising a frame adapted to support a printing form near one end thereof and to support two sets of spaced printing elements at its other end, one to receive negative transfers, and the other to receive positive transfers, a proof roller travelable over the printing form, negative and positive transfer rollers normally between said printing elements, the former of which is travelable across the negative printing element and over the printing forms, and means whereby said transfer rollers may be rotated in peripheral contact to transfer impressions from the negative transfer roller to the positive roller, said positive transfer roller being travelable over one of the printing elements to 65 transfer positive impressions thereon.
19. A proof and transfer press comprising a frame adapted to support a printing form near one end thereof and to support two sets of spaced printing elements at its other end, one to receive negative transfers, and the other to receive positive transfers, a proof roller travelable over the printing forms, negative and positive transfer rollers normally between said printing elements, 70 the former of which is travelable across the negative printing element and over the printing form, means whereby said transfer rollers may be rotated in peripheral contact to transfer impressions from the negative transfer roller to the positive roller, said positive transfer roller being travelable over one of the printing elements to transfer positive impressions thereon, and a support for the latter printing element, combined 75 with means for adjusting said support transversely of the frame.
20. A proof and transfer press comprising a frame, a proof roller, a bed beneath the same adapted to support a printing 80 form, means to support printing elements spaced longitudinally of the frame, and transfer means to receive impressions from the printing forms and constructed with means to either transfer said impressions as 85 negative transfers on one printing element or as positive transfers on another printing element.
21. In combination with a support for a printing form and a transfer element, of 100 two transfer rollers, one travelable over the printing form to receive impressions thereon, with means to cause said rollers to rotate in peripheral contact to transfer the impression from one roller to the other, and 105 means whereby the impressions are transferred from the latter roller to the transfer element.
22. A proof and transfer press comprising a frame, an adjustable bed thereon, 110 proof and transfer rollers rotatively supported on said frame, racks extending longitudinally of the frame, and gears on said rollers separately meshing with said racks.
- In testimony whereof I claim the foregoing as my invention, I hereunto append my signature at Chicago, Illinois, this 31st day of August, 1918.

LOUIS SMITH.
